UNITED STATES PATENT OFFICE.

JAMES H. W. MARRIOTT, OF WASHINGTON, DISTRICT OF COLUMBIA.

TYPE-WRITER LINE-SPACING MECHANISM.

SPECIFICATION forming part of Letters Patent No. 759,817, dated May 10, 1904.

Original application filed March 19, 1903, Serial No. 148,611. Divided and this application filed December 5, 1903. Serial No. 183,910. (No model.)

To all whom it may concern:

Be it known that I, JAMES H. W. MARRIOTT, a citizen of the United States, residing at Washington, in the District of Columbia, have invented certain new and useful Improvements in Type-Writer Line-Spacing Mechanism, of which the following is a specification.

This invention comprises improvements in line-spacing mechanism for writing-machines which are bodily movable upon suitable guideways and adapted to write upon flat printing-surfaces, such as the machine shown in my application, Serial No. 148,611, filed March 19, 1903, of which the present application is a division.

In the accompanying drawings, Figure 1 is a side view of the main supporting-carriage for the writing-machine, mounted upon stationary guide-rails and provided with my improved spacing mechanism; and Fig. 2 is a plan view of the same, partly broken away.

Referring to the drawings, A and B indicate a pair of parallel rails or guideways, supported horizontally in fixed position at a suitable distance above the writing-bed by standards or uprights 1 and 2, which are secured to the guideways and to a supporting-table 3. Parallel toothed racks 4 and 4^a are formed or arranged upon the upper edge of each rail a short distance apart, leaving between the racks of each guideway a channel 5.

A supporting frame or carriage C for the printing mechanism is suspended between the machine-guideways by means of a pair of wide pinions 6, each extending across and engaging both racks of a guideway, and a pair of double pinions 7, each engaging both racks of a guideway and having a central rib or disk 7^a, which extends into the channel 5. The main supporting-frame C consists of a pair of similar triangular side plates or hangers 8 and 8^a and cross-bars 9 and 10, connecting said hangers with one another. The pinions 6 are journaled upon studs 11, secured to the forward ends of the hangers, and the pinions 7 are fixed to the ends of a shaft 12, which is journaled in the rear ends of the hangers. The disks 7^a, fitting within the channels 5, prevent any side play of the frame, and as all of the pinions

have a wide bearing on the racks the frame is held rigidly against any twisting tendency in operation. A rack-bar 13 is journaled in the lower part of the supporting-frame, and the writing mechanism is carried by a frame secured to this rack-bar, but not herein shown, as this mechanism forms no part of the invention claimed herein.

The supporting-frame C, which carries the printing mechanism, is movable longitudinally of the machine-guideways with a step-by-step motion for line-spacing by means of a spacing-lever 14, fulcrumed upon a stud 15, projecting laterally from the hanger 8^a, a short pawl-carrying lever 16, fulcrumed upon a stud 17, also secured to said hanger, and a spring-pawl 18, pivoted to one end of the short lever and engaging a ratchet-wheel 19, which is secured upon the end of the pinion-shaft 12. The levers 14 and 16 lie normally at an angle to one another, as shown, the lever 16 having a slot 20 which is engaged by a pin 21 upon the lever 14 and the latter being held in the position shown by a spring 14^a, connected to the lever 14 and to a bracket 22 upon the hanger 8^a. The pawl is held in engagement with the ratchet-wheel 19 by a spring 23. The arrangement is such that when the forward end of the spacing-lever 14 is depressed the pawl will be depressed and the ratchet-wheel and shaft 12 will be turned, thereby causing the pinions 7, which are secured to the shaft and engage the rack, to move the carriage forward, as will be evident from an inspection of the drawings. The distance to which the machine moves at each operation of the spacing-lever is determined by adjustable stops 24 and 25, which are supported by brackets 22 and 26 upon the hanger 8^a. These stops limit the movement of the spacing-lever in both directions. A spring holding-pawl 27, pivoted to an offset end 28 of the hanger 8^a, normally prevents backward rotation of the ratchet-wheel, and hence prevents backward movement of the entire mechanism. The moving pawl 18 and the holding-pawl 27, which are pivoted at opposite sides of the ratchet-wheel, are provided with upwardly-extending arms 18^a and 27^a, respectively, in line with pins or projections 29 and 30, which are secured to a

longitudinally-movable push-rod 31, mounted in bearings 32 and 33 at opposite ends of the hanger 8^a. A spring 34, interposed between the bearing 32 and a knob 35 at the forward 5 end of the push-rod, normally holds said rod in its forward position with the pins 29 and 30 out of engagement with the arms upon the pawls. When it is desired to move the machine rearwardly upon the guideways, however, the push-rod is pressed backward and the pins 29 and 30 engage the arms upon the pawls and lift both pawls out of engagement with the ratchet-wheel. After the pawls have become disengaged a stop-pin 36 upon the push-rod 15 engages the bracket 26 upon the supporting-frame, and the continued rearward pressure upon the push-rod then forces the machine rearwardly upon the guideways. The mechanism may at any time be drawn forward upon 20 the guideways without operating the spacing-lever by grasping any convenient part of the machine and pulling it forward.

Having described my invention, what I claim, and desire to secure by Letters Patent, 25 is—

1. In a type-writing machine, the combination with a pair of parallel machine-guideways, each guideway having a pair of parallel racks thereon, of a machine-supporting carriage having pinions engaging said racks, said pinions having disks or ribs fitting between the racks and preventing lateral movement of the frame.
2. In a type-writing machine, the combination with a pair of parallel machine-guideways, each guideway having a pair of parallel racks thereon, of a machine-supporting carriage having pinions at its front and rear ends engaging both racks of each guideway, one 40 or more of said pinions having ribs or disks extending between the racks.
3. In a type-writing machine, the combination with a pair of parallel machine-guideways having racks thereon, of a machine-supporting carriage, a shaft journaled in said carriage and having pinions secured to its ends and engaging said racks, a ratchet-wheel upon said shaft, moving and holding pawls normally engaging said ratchet-wheel, a spacing-lever 45 arranged to operate the moving pawl for line-spacing, and a device for moving and holding both of said pawls out of engagement with the ratchet-wheel.
4. In a type-writing machine, the combination with a pair of parallel machine-guideways having racks thereon, of a machine-supporting carriage, a shaft extending transversely of said carriage and journaled therein,

pinions secured to the ends of said shaft and engaging said racks, a ratchet-wheel upon 60 said shaft, moving and holding pawls normally engaging said ratchet-wheel, a spacing-lever arranged to operate the moving pawl for line-spacing, a push-rod having parts adapted to engage and move said pawls away 65 from the ratchet-wheel when the push-rod is moved in one direction, a stop upon said rod adapted to engage a part upon the frame when the rod is moved to release the pawls, and means for holding the push-rod out of 70 engagement with the pawls.

5. In a type-writing machine, the combination with a pair of parallel machine-guideways having racks thereon, of a machine-supporting carriage, a shaft extending transversely of said carriage and journaled therein, 75 pinions secured to the ends of said shaft and engaging said racks, a ratchet-wheel upon said shaft, a pawl-carrying lever pivoted to said frame and having a pawl thereon adapted to engage and turn the ratchet-wheel, and a spacing-lever pivoted to the frame and adapted to rock the pawl-carrying lever.

6. In a type-writing machine, the combination with a pair of parallel machine-guideways having racks thereon, of a machine-supporting carriage, a shaft extending transversely of said carriage and journaled therein, 85 pinions secured to the ends of said shaft and engaging said racks, a ratchet-wheel upon 90 said shaft, a pawl-carrying lever pivoted to said frame and having a pawl thereon adapted to engage and turn the ratchet-wheel, a spacing-lever pivoted to the frame and adapted to rock the pawl-carrying lever, and an adjustable stop for limiting the movement of the 95 spacing-lever.

7. In a type-writing machine, the combination with a pair of parallel machine-guideways having racks thereon, of a machine-supporting carriage, a shaft extending transversely of said carriage and journaled therein, 100 pinions secured to the ends of said shaft and engaging said racks, a ratchet-wheel upon 105 said shaft, a pawl-carrying lever pivoted to said frame and having a slot in one end and a pawl at its opposite end, said pawl being adapted to engage and turn the ratchet-wheel, and a spacing-lever pivoted to said frame and having a pin or projection engaging said slot. 110

In testimony whereof I affix my signature in presence of two witnesses.
